UNITED STATES PATENT OFFICE.

ERNEST ALFRED SUTER, OF ANCOATS, MANCHESTER, ENGLAND.

AZIMUTH-FITTING FOR MARINERS' COMPASSES.

1,401,205.

Specification of Letters Patent.

Patented Dec. 27, 1921.

Application filed August 9, 1919. Serial No. 316,463.

To all whom it may concern:

Be it known that I, ERNEST ALFRED SUTER, a subject of the King of Great Britain, and resident of Ancoats, Manchester, 5 in the county of Lancaster and Kingdom of England, have invented certain new and useful Improved Azimuth-Fitting for Mariners' Compasses, of which the following is a specification.

10 The present invention relates to a compass adjuster or corrector whereby a mariner may ascertain at a glance any compass error or any deviation and adjust it straight away without the necessity of chartroom obser- 15

vation.

The device of the present invention is applicable directly to any compass bowl. It consists of a frame adapted to move around the compass bowl on suitable guides which 20 may be partly formed of the rim of the bowl itself. This frame carries a graduated arc preferably detachable and a pair of pointers one being adapted to coöperate with the compass card and the other coöperating 25 with the said scale or arc.

The invention is more particularly described with reference to the accompanying drawings in which:—

Figure 1 is a plan view of the device at- 30 tached to a compass.

Fig. 2 is a perspective view of the device while

Fig. 3 is a section on the line 2—2 of Fig. 2.

35 A compass 5 with its card 6 of any known construction has mounted upon it the device of the present invention consisting of a frame of brass or other suitable non-magnetic material having a central box 8 having 40 arms 9, 10 and 11. The arms 9 and 10 are connected by an arc shaped strip 12 which projects beyond and conforms to the periphery of the compass bowl while grooves 13 and 14 are arranged on the arm 11 and arc 45 12 respectively to conform to the contour of the bowl 5 and engage to the rim of this so that the device can be adjusted around the rim of the bowl coaxially with the compass card but the device is held against 50 lateral movement.

A graduated arc, which may be of metal,

but which is preferably of white transparent opal glass 15, is secured at its ends to the arms 9 and 10 by means of adjusting screws 16. The graduations on the arc range from 55 the center line shown at 17 on the drawing both right and left from 0° to 55° east and west are shown in Figs. 1 and 2. This arc is preferably detachable so that either a metal arc or a transparent arc for use at 60 night can be set up on the device.

In use to determine any deviation in the compass needle from the correct position a horizon glass 19 is mounted on a pivot carried in standards 21, projecting upwardly 65 and centrally off the arc shaped strip 12. The horizon glass is arranged to receive the sun's rays as reflected from the index glass 20 pivoted between standards 22 on the arm 11. The index glass 20 and horizon glass 70 19 are manipulated by means of milled heads 26 and 27 on their respective pivots. If desired a colored shade 23 pivoted to the standards 22 may be swung into position in the light ray path. 75

A pointer 25 recording the true bearing is mounted to be freely rotatable about a spindle 28 projecting upwardly from the bottom of the hub 8. The lower end of the spindle 28 is pointed and protrudes downward and is used for pivoting on the center 80 of the compass.

A second pointer 29 is adapted to indicate the variation of the compass on the arc 15 and is mounted on a fixed spindle 39 depend- 85 ing centrally from the top of the hub or box of the device in alinement with the stub 28. These pointers 25 and 29 are manipulated by means of thumb screws 30 and 31 connected to shafts 32 and 33 the ends of which 90 have mounted gears 34 and 35 meshing with gears 36 and 37 carried by the respective spindles 28 and 39 of the pointers.

The longest pointer 25, is set to the true bearing (taken from tables) on the compass card, the observed bearing being registered by the reflected sun, star, or other object on the center line by the horizon mirror 19. This is the error which is named on the arc. The other or shorter pointer 29 is 100 then set to indicate the variation on the arc. The difference between the two pointers

shown on the arc is the deviation. As an example:—

A bearing taken by azimuth of the sun.

5 True bearing	N. 73° east
Observed bearing	N. 75° east
Error	2° west
10 Variation	14° west
Deviation	12° east

I declare that what I claim is:—

1. A compass corrector comprising a frame, a graduated arc carried by said frame, means to mount said frame on a compass bowl so that said arc and compass card will be concentric, a pair of needle pointers pivoted in the frame and coöperating with said 15 arc and with the compass card, one to indicate the true bearing and the other to indicate the compass error as a direct reading.

2. A compass corrector comprising a frame, a graduated arc carried by said frame, means to mount said frame on a compass bowl so that said arc and compass card will be concentric, a pair of needle pointers pivoted in the frame and coöperating with said arc and with the compass card, one to indicate the true bearing and the other to indicate the compass error as a direct reading, coaxial spindles mounted in the frame and respectively carrying said needle pointers, a separate operating head for each spindle and gearing connecting each head 30 with one of said spindles.

In witness whereof, I have hereunto signed my name this 16th day of July, 1919, in the presence of two subscribing witnesses.

ERNEST ALFRED SUTER.
